TRANSFORMER RELIEF DIAPHRAGM

Filed Oct. 4, 1924

Fig. 1

UNITED STATES PATENT OFFICE.

LELAND H. HILL, OF SWISSVALE, AND WALTER M. DANN, OF WILKINSBURG, PENNSYLVANIA, ASSIGNEES TO WESTINGHOUSE ELECTRIC & MANUFACTURING COMPANY, A CORPORATION OF PENNSYLVANIA.

TRANSFORMER RELIEF DIAPHRAGM.

Application filed October 4, 1924. Serial No. 741,641.

Our invention relates to electrical translating devices and particularly to devices for indicating the occurrence of excessive pressures therein.

5 One object of our invention is to provide an electrical translating device with means for indicating the occurrence of excessive pressures therein.

Another object of our invention is to provide 10 an indicating device that shall operate upon the rupture of a relief diaphragm.

A further object of our invention is to provide 15 an electrical translating device that shall give both a visual and an audible indication of the occurrence of pressure therein sufficient to rupture the relief diaphragm.

In electrical translating devices, such as 20 transformers and circuit interrupters, it is customary practice to partially fill the casting with oil in such manner that a relief diaphragm placed in the upper part of the translating device is liable to rupture upon the occurrence of excessive pressures in the translating devices rather than at seams and 25 joints of the electrical devices themselves.

In our co-pending application, Serial No. 608,773, filed Dec. 23, 1922, is shown and described a preferred disposition of such relief diaphragms in the cover of electrical 30 translating devices. The present invention provides indicating means that shall operate upon the rupture of such diaphragms.

In the accompanying drawings,

Figure 1 is a side-elevational view of an 35 electrical translating device embodying our invention.

Fig. 2 is a fragmentary view, partially in elevation and partially in section, of the 40 electrical translating device shown in Fig. 1.

Fig. 3 is a fragmentary view, partially in elevation and partially in section, of the translating device shown in Fig. 1.

Fig. 4 is a sectional view of a detail of our invention taken along the section line 45 IV—IV in Fig. 2.

Our invention comprises, in general, an electrical translating device 1, such as a transformer or circuit interrupter, provided with a relief diaphragm 2 and a cover 3, together with an indicator 4 that operates upon the rupture of the relief diaphragm.

Referring to Fig. 3, the relief diaphragm 2 is secured in the cover member of the

translating device 1 below the cover member 3 that, in turn, is yieldingly attached to the 55 translating device 1 by bolts and springs 5 in order that it may be movable relatively to the diaphragm 2 and the translating device 1. An ear 6 is provided on the cover member 3 and a perforation or hole 7 is 60 formed therein.

Indicating device 4 comprises a target 8 that is supported on the translating device 1 by a horizontally disposed rod 9 that traverses supporting lugs 11, 12 and 13. One 65 end of the rod 9 terminates in a pin 14 that co-operates with the opening 7 in the cover member 3. A coil spring 15 is attached to the support 12 at one end and, at the other end to a pin 16 carried by the rod 9, thereby 70 placing the coil spring in tension when the pin 14 is in opening 7.

Referring to Fig. 4, the support 12 is provided with a pair of stationary contact members 17 that co-operate with a contact member 19 carried by the pin 16 for completing an electrical circuit 21 comprising an audible 75 alarm 22 and an indicating lamp 23.

Upon the assembly of the electrical translating device 1, the diaphragm 2 is mounted 80 thereon and the cover member 3 placed thereover, with the pin 14 registered in the opening 7. The rod 9 is thereby retained in its left hand position against the bias of the spring 15, and the target 8 is retracted behind the edge of the translating device 1.

Upon the occurrence of excessive pressure in the translating device 1, due to any cause whatsoever, such that the relief diaphragm 2 is ruptured, the cover member 3 is raised 90 against the springs 5 during the escape of fluid under pressure. The upward movement of the cover member 3 is sufficient to release the pin 14 from the hole 7, whereupon the rod 9 moves to its dotted-line position in Fig. 2 and projects the target 8 beyond the edge of the translating device 1. At the same time, the movable contact member 19 engages the stationary contact members 17 and completes the electrical circuit 23 to cause the audible signal 22 and the visual signal 23 to function.

In order to re-set the indicating device 4, it is necessary to lift the cover member 3 and move the pin 14 into registry with opening 7, after which the cover 3 is lowered.

This operation retracts the target 8 and places the spring 15 under tension for a subsequent operation of the indicating device.

Our indicating devices are particularly useful in connection with transformer banks where it is necessary to quickly ascertain which one of a number of transformers is at fault without rendering the entire number of transformers electrically inactive and making necessary an internal inspection of each.

It is to be understood that such changes may be made in the disposition of the several parts constituting our invention and structural details thereof as fall within the scope of the appended claims.

We claim as our invention:

1. The combination with a closed casing comprising a relief diaphragm that is adapted to be ruptured in case of excessive pressure in said casing, of a visual indicating device operable upon the rupture of the diaphragm.

2. The combination with a closed casing comprising a relief diaphragm and a cover member therefor that is movable upon the rupture of said diaphragm because of excessive pressure in said casing, of an indicating device connected to said cover member and operable upon the rupture of the diaphragm.

3. The combination with a closed casing comprising a relief diaphragm and a cover member therefor adapted to be actuated upon the rupture of said diaphragm, of means controlled by the cover member for indicating the rupture of the diaphragm.

4. The combination with a closed casing comprising a relief diaphragm and a movable cover member therefor, a spring-actuated

indicator controlled by the cover member 40 and released upon predetermined movement thereof upon the rupture of the diaphragm.

5. The combination with a closed casing comprising a relief diaphragm and a cover member therefor that is movable upon the 45 rupture of the diaphragm, of an indicator released by the cover member upon the occurrence of predetermined movement of the latter.

6. The combination with a closed casing 50 comprising a relief diaphragm, and a loosely mounted cover member therefor, of a spring-actuated indicator coacting with said cover member and detachably retained thereby in a biased position.

7. The combination with a closed casing comprising a relief diaphragm, and a loosely mounted cover member therefor, of a spring-actuated indicator comprising a pin coacting 60 with said cover member, movement of said cover member detaching said pin therefrom to permit movement of said indicator under the influence of its actuating spring.

8. The combination with a casing containing an insulating liquid medium for electrical apparatus generating heat during operation thereof, of controlled mechanism, and means comprising a rupturable diaphragm for effecting the actuation of said controlled mechanism, said means being responsive to 70 the occurrence of predetermined pressure in said casing.

In testimony whereof, we have hereunto subscribed our names this first day of October, 1924.

LELAND H. HILL.
WALTER M. DANN.
